CLAIM

We claim the ornamental design for a tire tread for a model vehicle, as shown and described.

DESCRIPTION

FIG. 1 is a, top, left, front perspective view of a tire tread for a model vehicle;

FIG. 2 is a front elevation view thereof;

FIG. 3 is a side elevation view thereof;

FIG. 4 is a perspective view of a model vehicle showing a state in which the tire tread is on a tire in a left-front position on the model vehicle;

FIG. 5 is a perspective view of a model vehicle showing a state in which the tire tread is on a tire in a left-rear position on the model vehicle;

FIG. 6 is a perspective view of a model vehicle showing a state in which the tire tread is on a tire in a right-front position on the model vehicle; and,

FIG. 7 is a perspective view of a model vehicle showing a state in which the tire tread is on a tire in a right-rear position on the model vehicle.

Structural elements depicted by broken lines have been shown for the purpose of illustrating portions of a tire for a model vehicle, and its environment, that form no part of the claimed design. The dot-dash broken lines define the bounds of the claimed design and form no part thereof. The appearance of the front of the tire tread for a model vehicle is repeated around the top, bottom, and rear of the tire tread for a model vehicle. The appearance of the right side of the tire tread for a model vehicle is a mirror image of the left side of the tire tread for a model vehicle.
